ATTACHMENT FOR ARTIFICIAL LEGS

Filed Aug. 13, 1931

Inventor
James A. Swain
by Wilkinson & Mawhinney
Attorneys.

UNITED STATES PATENT OFFICE

JAMES ARTHUR SWAIN, OF LONDON, ENGLAND

ATTACHMENT FOR ARTIFICIAL LEGS

Application filed August 13, 1931, Serial No. 556,872, and in Great Britain September 4, 1930.

This invention relates to an attachment by means of which an artificial leg can be supported from the body of the user in such manner that the support yields or moves 5 automatically in accordance with movements of the hip joint, these latter movements being unobstructed by the attachment, which has not been the case with previous attachments of this kind.

10 The attachment according to this invention comprises a belt adapted to be passed around the waist of the wearer and carrying two straps which are connected to the artificial limb, and which cross each other both 15 at the front and rear of the body of the wearer beneath the belt, at a point approximately at the level of the hip joint, this arrangement being necessary to insure unrestricted movement of the hip joint and securing the artificial limb to the body to a corresponding degree in any movement of the body.

Each strap passes through one of a pair 20 of loops or the like, the two loops being respectively secured to opposite sides of the artificial limb. Each of the straps is secured to the belt at two places.

The invention is illustrated in the annexed drawing, which is a perspective view.

In this drawing, *a* represents the waist 30 belt and *b* the artificial limb, the limb *b* being supported from the belt by means of the crossed straps *c* and *d*, which as shown cross both in the front at *e* and in the rear at *f*. The limb *b* is provided at each side with a 35 loop *g* or the like through which a strap passes freely. Each strap is attached to the belt at two places, and one of the attachments may in the case of each strap be adjustable, as for instance a buckle and strap.

40 Having thus described the nature of the said invention and the best means I know of carrying the same into practical effect, I claim:

1. An attachment by means of which an 45 artificial leg can be supported from the body of the user, such attachment comprising a belt to which two straps connected to the limb are secured each in two places, the two straps being so arranged that they cross each 50 other at the front and rear of the body of the

wearer, beneath the belt at a point approximately at the axis of the hip joint, this arrangement providing unrestricted movement of the hip joint and securing the artificial limb to the body to a corresponding degree in any movement of the body.

2. An artificial leg attachment according to claim 1, in which each strap passes freely through one of a pair of loops or the like secured to the limb.

In testimony whereof I have signed my name to this specification.

JAMES ARTHUR SWAIN. [L. S.]
